(57) **CLAIM**

The ornamental design for a toy, as shown and described.

DESCRIPTION

FIG. 1 is a first perspective view of a toy showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 1;

FIG. 11 is an enlarged view of the selected portion 11 in FIG. 1; and,

FIG. 12 is an enlarged view of the selected portion 12 in FIG. 2.

The broken lines shown in the drawings depict portions of the toy that form no part of the claimed design. The toy is shown broken away in FIGS. 1-4 and 7-8 to indicate that no particular length is claimed. The toy is shown with a symbolic break in its length. The area between the break lines forms no part of the claimed design.
